CLAIM

The ornamental design for a motorcycle stereo mounting device, as shown and described.

DESCRIPTION

FIG. 1 is a perspective view of a motorcycle stereo mounting device showing my new design;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view of thereof; and,

FIG. 8 is a bottom plan view of thereof.

The broken lines in the drawings illustrate portions of the motorcycle stereo mounting device that form no part of the claimed design.

1 Claim, 8 Drawing Sheets
